UNITED STATES PATENT OFFICE.

JOSEPH N. MAHONEY, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,199,477.

Specification of Letters Patent. Patented Sept. 26, 1916.

Application filed February 1, 1913. Serial No. 745,618.

To all whom it may concern:

Be it known that I, JOSEPH N. MAHONEY, a citizen of the United States, and a resident of Wilkinsburg, in the county of Allegheny, 5 and State of Pennsylvania, have invented a new and useful Improvement in Circuit-Interrupters, of which the following is a specification.

My invention relates to circuit interrupters and it has special reference to interrupters of the so called "oil" type that are particularly adapted to handle large amounts of current at high voltages.

One of the objects of my invention is to 15 simplify and improve the operation and construction of devices of the above indicated character, and to provide a device that shall be compact and rugged in construction and particularly adapted to perform its intended 20 functions with reliability and effectiveness under severe operating conditions.

Another object of my invention is to provide a circuit interrupter of this general 25 class that is adapted to be operated electrically with great rapidity and positiveness, during both its closing and operating movements.

Another object of my invention is to provide adequate and effective means for cushioning the heavy moving parts and absorbing the shocks incident to the opening and closing operations.

Another object of my invention is to provide an oil containing receptacle for the relatively movable contact members that shall be of great strength and durability in order to withstand the high pressures developed therein at the instant the circuit is interrupted, and to provide also a liberal expansion chamber above the oil level in the receptacle, which chamber is vented to the atmosphere through a baffled opening, whereby the pressures developed may be relieved without permitting the escape of any of the 45 insulating oil.

A still further object of my invention is to provide means for materially decreasing the reaction pressures upon the movable contact members during the opening operation, 50 thereby permitting a rapid acceleration of the moving parts at the instant of interruption.

In the prior art, considerable difficulty has been encountered with circuit interrupters of 55 the class that has been employed in genera-

ing or distributing systems of large capacity and high voltage, by reason of the relatively weak mechanical construction of the apparatus as well as the lack of provision to suit the requirements of an interrupter that is subjected to severe operating conditions. It is well known that, when circuits of considerable capacity are interrupted under oil, excessive pressures are produced during the intervals in which the arcs are being ruptured, and these pressures have frequently disabled, and in some cases, have "blown up" the interrupting devices. I have made a careful study and investigation of this problem and have determined that, in general, interrupters of this class are relatively weak in structure and operate too slowly for best results.

According to my invention, therefore, I have made particular provision for securing a rapid acceleration of the moving parts during the opening operation in order that the circuit may be interrupted in a minimum time interval, and have also improved and strengthened the structural details of the containing tanks to render them better adapted to withstand excessive pressures.

By reason of the rapid movement of the heavy movable parts, it has also been necessary to provide means for retarding the movement thereof near the end of the stroke in order to prevent the parts from being subjected to severe jolts and shocks.

These and other features for improving the construction and operation of large-capacity circuit interrupters constitute my present invention and will be hereinafter more fully disclosed and set forth in the specification and claims.

My invention may be best understood by reference to the accompanying drawings in which—

Figure 1 is a view, partially in side elevation and partially in section, of a circuit interrupter constructed in accordance with my invention. Fig. 2 is a plan view of the device shown in Fig. 1. Fig. 3 is a view of a portion of the device shown in Fig. 1, the view being taken at right angles to that of Fig. 1 and being shown partially in section. Fig. 4 is a sectional view taken along the line IV—IV of Fig. 3. Fig. 5 is an end elevation of the supporting structure of one of the containing tanks, and Figs. 6 and 7 are enlarged views, respectively in section

and in plan, of certain details of construction shown in Fig. 1.

Referring to the drawings, the apparatus here shown comprises a multi-polar interrupter of the "oil break" type which embodies a supporting plate or bed 1 having a plurality of tanks or receptacles 2 and expansion chambers 3 suspended therefrom, and, mounted upon the bed-plate 1, is an operating mechanism 6, a plurality of operating electromagnets 7, a plurality of auxiliary accelerating devices 8, a latching device 9, a tripping device 10, a plurality of dash-pots or shock absorbers 11 and 11^a, and a yoke or supporting member 12 from which a plurality of movable contact members 13 are suspended by means of suspension rods 15 that project through suitable openings in the bed-plate 1. The several movable contact members 13 are adapted to co-operatively engage a plurality of stationary contact terminals 14 in a well-known manner.

The bed-plate 1 is supported in position by several walls or partitions 16 of brick, cement or other suitable insulating material, thereby providing a plurality of cells or compartments 17 to receive the several tanks 2 and to separate them, one from another, in accordance with well known construction.

The apparatus pertaining to each of the poles of the interrupter and the structure and arrangement of its component parts are alike and each comprises an expansion chamber 3, which is suitably suspended beneath the bed-plate 1 by means of a plurality of insulating supports 19 which are suitably attached to the bed-plate 1, and the upper portion of the expansion chamber 3. The tank 2 is constructed of sheet material and serves to contain an insulating oil in which the co-operating contact members 13 and 14 are immersed. The tank 2 is preferably of elliptical form, and the main portion thereof is fitted within an outer flange 2^a of the bottom portion in order to provide a rugged and strong structure. To suspend the tank 2 firmly from the expansion chamber 3 and to clamp the chamber and the tank rigidly together to form a unitary and strong structure, bolts 20, tie rods 20^a and a clamping plate 20^b are employed. The bolts 20 are used in accordance with well-known practice and the tie-rods 20^a co-operate with the clamping plates 20^b and suitable parts of the expansion chamber whereby the tank 2 is detachably held securely in position and prevented from being blown apart from the expansion chamber. A flange construction or joint 21 is employed between the lower portion of the expansion chamber 3 and the upper portion of the tank 2 to strengthen and reinforce the tank 2 and to prevent its being expanded by the high

pressure developed within it during the period of interruption.

Projecting through the upper wall 22 of the expansion chamber 3 are a plurality of insulators 24, through which conductors or cables 25 extend. The ends of the cables 25 terminate in the stationary contact terminals 14 which are adapted to be engaged by the respective ends of the movable contact member 13 when the interrupter is in its closed position.

The movable contact member 13 preferably comprises a main contact member 27 of laminated copper and a plurality of auxiliary arcing contact terminals 28, which are adapted to co-operate with the stationary contact terminals 14 in the usual manner for the purpose of accomplishing the final interruption of the circuit, as will be readily understood. The specific structural details of the stationary contact terminals 14 and the movable contact member 13 pertain only indirectly to my present invention, and any other suitable devices for performing the same functions and securing the same results may be employed.

The tank 2 is substantially filled with an insulating oil 30 which completely immerses the co-operating contact members 13 and 14 and an elliptical or otherwise suitably formed insulating barrier 31 is disposed within the tank between it and the contact members.

The expansion chamber 3 is of liberal capacity and is reinforced in a lateral direction by means of webs or cross supports 32. Furthermore, the expansion chamber 3 is provided with an upwardly projecting tube or pipe 33 which serves to communicate to the outside atmosphere, thereby permitting any pressure that may be produced in the expansion chamber, by reason of the formation of arcs at the instant of circuit interruption, to be relieved. The vent pipe 33 is provided with a plurality of vertically arranged and centrally disposed substantially conical baffle members 33^a. Each of the baffle members 33^a is provided with a segmental recess 34 and the several recesses are staggered or "off set" with respect to one another, so that an obstructed tortuous path to the atmosphere is provided. Thus any pressure within the expansion chamber 3 may be relieved, while the oil is prevented from being thrown out at the same time.

The several suspension rods 15 are of like construction and each preferably comprises upper and lower sections 35 and 36, respectively, of insulating rods, and an intermediate portion 37 of steel or other material having a relatively small sectional area. The intermediate steel rod 37 projects into the expansion chamber 3 through a bearing or stuffing box 38, which closely surrounds the rod and prevents communication to the

atmosphere. The rod 37 need not necessarily constitute an intermediate section but may form the entire supporting rod above the lower section 36. The rod 37 must however be of as small sectional area as is possible, consistent with the requisite strength, for the purpose of reducing the area upon which the pressure in the chamber may act when the separation of the movable co-operating contact members is effected. Thus, the resultant pressure acting against the movable members is reduced to a minimum, thereby permitting a rapid acceleration of the moving parts at the instant of circuit interruption. This feature is of particular importance as it contributes toward quick operation of the interrupter, which is necessary in order to rupture large amounts of current at comparatively high voltages without undue disturbance of the distributing system and without danger of accident or damage to the interrupter itself.

The operating mechanism 6 may be of any suitable type that is adapted to secure the desired vertical movement of the yoke or supporting member 12 and its attached movable contact members 13. The operating mechanism shown, comprises a main operating lever 40 embodying a plurality of parallel arms 41 that are severally pivotally mounted intermediate their ends upon pins 42. One end 43 of each of the arms 41 is pivotally connected to one of the arms 45 of a supporting member or lever 44 substantially midway between its ends by pins 43^a. The arms 45 are substantially parallel and the outer ends 46 of the same are pivotally connected to the upper end of a link 47 by means of a pin 48. The lower end 49 of the link 47 is pivotally attached to the bedplate 1 in a suitable manner. The yoke or supporting member 12 is disposed between the arms 45 of the supporting member 44 and is pivotally associated with the free ends thereof through the agency of a pin 51.

The outer ends of the operating levers 41 are provided with segmental portions 52 to which chains or other suitable flexible members 53 are attached. The other end of each 50 of the chains 53 is fastened to a movable core member 54 of each of the electro-magnets 7 which are adapted to actuate the operating mechanism hereinbefore described during the closing operation.

55 The particular structure of the electro-magnets 7 forms no material part of my present invention and I do not wish to be restricted in this respect inasmuch as electro-magnets of any well-known construction 60 may be employed.

Each of the segmental portions 52 is provided with a projecting member or lug 56 to which is pivotally connected one end of a rod 57 that is centrally disposed within a 65 tubular member 58, the lower end 59 of

which is pivotally attached to the bed-plate. 1. A heavy coil spring 60 surrounds the rod 57 within the tubular member 58 and is adapted, by reason of the structure and arrangement of parts, to be placed under tension during the closing operation and to assist gravity in accelerating the moving parts when the interrupter is opened. 70

The latching device 9 comprises links 62, the upper ends of which are pivotally connected to the arms 45 by means of the pins 43^a, while the lower ends thereof are pivotally connected to the upper ends of a plurality of triangular-shaped members 63, having suitable pivotal connections to the bed-plate 1. A weighted portion 64, constituting one corner of the triangular member 63, is adapted to engage an adjustable stop 65. When the interrupter is in its closed position, the links 62 and members 63 together constitute a toggle which is slightly "over-set" across its dead center position, thereby restraining the operating mechanism. 80

The tripping device 10 comprises a bell 90 crank lever 66 which is pivotally mounted upon a pin 67, arms 68 of which are adapted to engage the upper ends of the members 63 under predetermined operating conditions and to thereby release the latching device 95 hereinbefore described. A suitable electro-magnet 69 is attached to the outer end 70 of an integral arm 71 of the bell crank lever 66 and is thus adapted to actuate said lever to trip out the interrupter, in accordance 100 with predetermined conditions. The bell crank lever 66 is provided with a weighted member 72 for the purpose of returning it to its normal position.

In order to retard the movement of the 105 movable parts of the interrupter and to prevent destructive heavy shocks to the mechanism, during the opening operation of the interrupter, a plurality of dash-pots 11 are disposed directly beneath the yoke member 110 12 on opposite sides of the middle suspension rod 15. The several dash-pots 11 may be of any suitable construction and are provided with spring-supported piston rods 74 and with adjustable relief valves 75 for the purpose of regulating the action thereof. The 115 several dash-pots 11 are suitably mounted upon a bracket 76 which constitutes an integral part of a plurality of upwardly projecting supporting members 77, upon the 120 upper ends of which a third dash-pot 11^a is mounted to be engaged by the yoke member 12 during the closing operation of the interrupter for cushioning the movable parts.

Assuming the various parts of the apparatus to occupy the positions shown in Figs. 1 and 2, the closing operation is as follows: Electrical energy is first supplied to the operating electro-magnets 7 from any suitable source, which, when energized, pull down 125

their respective movable core members 54 and thereby cause a clockwise rotative movement of the operating lever 40 about its pivoted supports 42 through the chains 53. 6 Thus, the outer ends of the operating lever 40 are moved upwardly and, since they are pivotally associated with the supporting member 44 at a point intermediate its ends, it is evident that the inner end 51 thereof is 10 raised. By reason of the pivotal mounting of the link 47, the end 51 of the operating member 44 is moved in substantially a straight vertical line, thereby raising the yoke member 12 and its associated movable contact member 13. During this operation, the movable contact members 13 are severally brought into coöperative engagement with their stationary contact terminals 14, thus closing the several poles of the 15 interrupter. During the operation just described, the latching toggle comprising the links 62 and 63 is brought beyond its dead center position and thereby serves to maintain the operating mechanism in its closed position. 20 Furthermore, it will be understood that, as the operating mechanism is being actuated to effect the closure of the interrupter, power is being stored in the several tension springs 60 to be available for use in rapidly accelerating the movable breaker parts when the interrupter is tripped. When the several parts substantially reach their upper positions, their movement is retarded and cushioned by the upper dash-pot 11^a. This 25 function is particularly desirable when the electro-magnets 7 are operated from a line upon which the voltage varies through a wide range, for the reason that, if the electro-magnets 7 should be energized at a particularly high voltage, an excessive shock 30 would be sustained by the operating mechanism, unless otherwise absorbed.

In order to release the interrupter, it is only necessary to energize the electro-magnet 45 69, either at the will of the operator or by the occurrence of predetermined circuit conditions for which the electro-magnet is adjusted. Thus, the tripping levers 68 are suddenly projected against the locked latching toggle, whereby it is collapsed to permit 50 the operating mechanism to be opened. At the instant the latching toggle is tripped, gravity and the auxiliary power springs 60, in which energy has been stored, act in conjunction to effect the separation of the co-operating contact members 13 and 14 at a 55 rapid rate. Thus, the circuit is suddenly opened and the arc formed as the contact members separate is ruptured effectively in 60 an extremely short interval of time. The downward movement of the heavy moving parts is arrested by means of the dash-pots 11, the several parts assuming the positions shown in Fig. 1.

65 During the separation of the co-operating

members 13 and 14 under the insulating oil, a great pressure is produced, as well as a violent formation of bubbles and gas which rise through the oil and may escape to the atmosphere through the expansion chamber 70 3 and the baffled opening 33. Furthermore, by reason of the expansion chamber and the vent opening, the pressure produced is largely relieved and reduced to a value that is not destructive to the apparatus. Moreover, by reason of the restricted cross sectional area of the rod 37 where it projects into the expansion chamber 3, there is practically no resultant pressure upon the movable contact members 13 to retard their 80 movement.

While I have shown and described my invention as embodied in a circuit interrupter having a plurality of poles and of specific structural details and arrangement and location of parts, those skilled in the art will readily understand that it is not restricted in this respect and that structures and devices differing considerably in details and arrangement may be constructed which will substantially secure the advantages and benefits of my invention. I, therefore, desire it to be understood that all modifications which do not depart from the spirit and scope of my invention are intended to be 95 covered by the appended claims.

I claim as my invention:

1. In a circuit interrupter, the combination with relatively movable contact members, and an oil-containing receptacle for said members, of an expansion chamber removably attached to said oil receptacle at its upper end, means for reducing the resultant pressure on the movable parts when the contact members separate, and a pipe 100 communicating with said expansion chamber and having a plurality of recessed conical members disposed therein.

2. In a circuit interrupter, the combination with stationary and movable contact members, of an expansion chamber supporting said stationary contact members, an oil receptacle removably attached to the lower end of said expansion chamber, and a pipe 105 communicating with said chamber and having a plurality of recessed conical members disposed therein.

3. In a circuit interrupter, the combination with relatively movable coöperating contact members, and an oil-containing receptacle for said members having an opening in the upper portion thereof, of a plurality of conical baffle members disposed in said opening, the several baffle members having staggered segmental recesses therein.

4. In a circuit interrupter, the combination with relatively movable coöperating contact members, of a liquid-containing tank for said members, a casing embodying an expansion chamber of liberal capacity dis-

posed above said tank and having an opening therein, and a plurality of recessed conical members disposed in the opening.

5. In a circuit interrupter, the combination with relatively movable coöperating contact members, and an oil-containing tank for said contact members, of a casing embodying an expansion chamber disposed above said tank and provided with a pipe 15
10 having a plurality of conical recessed baffle members therein.
6. In a circuit interrupter, the combination with relatively movable coöperating

contact members, of a liquid-containing tank for said members, a casing embodying an expansion chamber disposed above said tank, and a pipe communicating with said chamber and having a plurality of recessed conical members disposed therein.

In testimony whereof, I have hereunto 20
subscribed my name this 30th day of January, 1913.

JOSEPH N. MAHONEY.
